UNITED STATES PATENT OFFICE.

LEWIS COLE, OF CHICAGO, ILLINOIS, ASSIGNOR TO TALK-SING COMPANY, OF CHICAGO,
ILLINOIS, A CORPORATION OF ILLINOIS.

PHONOGRAPH.

1,244,588

Specification of Letters Patent. Patented Oct. 30, 1917.

Application filed September 1, 1916. Serial No. 118,025.

To all whom it may concern:

Be it known that I, LEWIS COLE, a citizen of the United States of America, and a resident of Chicago, county of Cook, and State of Illinois, have invented certain new and useful Improvements in Phonographs, of which the following is a specification.

This invention relates to phonographs suitably arranged for use in toys and other devices, such as cigar cutters, clocks, dolls, savings banks, etc.

The objects of the invention are to provide simplified and improved means for starting, stopping and governing the speed of devices of this class; to provide improved means for automatically disengaging the stylus at the end of operations of the device and restoring the stylus carrying arm to its initial position, ready to repeat operations; and to provide improved means for causing the stylus to resiliently engage a record.

An illustrative embodiment of this invention is shown in the accompanying drawings, in which—

Figure 1 is a front elevation of a phonograph constructed according to this invention.

Fig. 2 is a rear view.

Fig. 3 is a left side view.

Fig. 4 is a right side view.

Fig. 5 is a plan view.

Fig. 6 is a sectional elevation taken on the line 6—6 of Fig. 4.

Fig. 7 is a detail in section showing the record support.

Fig. 8 is a sectional detail taken on the line 8—8 of Fig. 2, and shows part of the starting and stopping spring lever.

This invention provides simplified and improved devices in the structure of small phonographs whereby the same may be produced at low cost, but still permit of a great number of operations thereof without any appreciable deterioration of the mechanism.

Power is supplied to the device by means of a small clock mechanism incorporated therein and comprising gears 1 to 6 inclusive, connecting a spring motor 7 with a rotatable record support 8. The record support 8 is fixed to a sleeve 9 surrounding a winding spindle 10 journaled therein. The winding spindle 10 is provided with a suit-

able key 11, and the inner end of the driving spring 7 is secured as usual to the winding spindle, the latter also having the usual 55 ratchet connection (not shown) to gear 1, whereby the spring may be wound without rotating the gear and serves to drive the gear during the unwinding of the spring. The outer end of the spring 7 is secured to a 60 tie rod 12, Fig. 3. For the purpose of limiting the winding of spring 7, spindle 10 carries fast an arm 13 in position to engage a fixed stop pin 14, Fig. 6.

The starting and stopping and the speed 65 of the device are controlled through a governor 15. The latter comprises a spindle 16 to which are secured pinion 17 and arm 18. The pinion 17 receives motion from the gear 5 with which it meshes, at such speed as to 70 cause the small weights 19 of the governor to become effective in shifting a disk 20 slidable on spindle 16 into engagement with pad 21, with more or less pressure, and against the action of spring 22 surrounding 75 the spindle. The weights 19 are supported in balanced relation by the pivoted links 23 connecting arm 18 with disk 20. Longitudinal thrust of spindle 16 is prevented by springs 24 bearing against the ends of the 80 spindle and supported by the frame plate 25 and bracket 26 on frame plate 27.

The sound reproducing disk 28 is mounted in the sound box 29 supported on frame plate 27. The disk or diaphragm 28 has attached centrally thereto a wire 31 connecting it to a pivoted stylus arm 32, the latter being provided with a jewel tip 33 for engagement with record surfaces. The stylus arm 32 is pivoted to an ear 34 of a swinging arm 35 90 which in turn is pivoted on a fixed post 36. Arm 35 is made of spring steel or some other resilient material to afford the required pressure between the stylus and record and still permit the stylus arm to be rocked clear of 95 the record without necessitating an extra pivot or universal joint. The arm 35 has a lateral extension 35.1 coacting with a restoring cam member 37 on an oscillating shaft 38. When shaft 38 is rocked, the swinging 100 arm is restored to normal position, after being driven along the record surface by engagement therewith.

For the purpose of raising and lowering

the stylus out of and into engagement with the record surface, the shaft 38 has a cut away portion 39 extending below the swinging arm 35 along its path of travel. Thus, 5 this portion of the shaft is made eccentric to its axis and normally permits the stylus to engage the record surface. Near the end of operations of the device, the shaft 38 is rocked on its axis and cams the arm 35 upwardly against its spring action, thus causing the stylus to be raised clear of the record before cam arm 37 engages the extension 35.1 and restores arm 35 to normal position. 10 The arm 13 on shaft 10 serves to rock shaft 38 as above described, by engagement with arm 40 fast to the latter shaft, Fig. 6. This 15 rocking motion of shaft 38 also results in an arm 41 fast thereto engaging a curved extension 42 of a spring arm 43 mounted on the supporting frame 25 by screw 44. Arm 43 is bent as shown in Fig. 5 and passes through a slot 45 in the frame 25. At its free end, it carries a brake pad 21 for engagement with the rotating disk 20 of the 20 governor, when this disk is shifted inwardly along shaft 16. The arm 43 therefore provides a resilient means for restraining the rotation of shaft 16 beyond the desired speed. When the arm 41 engages the extension 25 42 at the end of operations of the device, the arm 43 is shifted so that the pad 21 firmly grips the disk 20 and stops the machine. Arm 43 then assumes the position shown in Fig. 8, a notch 46 therein engaging 30 the edge of slot 45, thus retaining the arm 43 in moved position.

For the purpose of restoring shaft 38 to its normal angular position as shown in Fig. 2, a coiled spring 47 surrounds the shaft and 40 bears between the pin 48 thereof and tie bar 49 connecting the frames 25 and 27. The restoring of shaft 38 takes place upon a subsequent rotation of shaft 10 under the action of the winding key 11. The winding 45 motion of the shaft is in a direction opposite to that indicated by the arrow in Fig. 6. Thus, arm 13 moves out of engagement with the arm 40 on shaft 38. The brake pad 21 still remains in engagement with disk 20, 50 due to the fact that notch 46 in the arm 43 still resiliently engages the edge of slot 45. In order to release the arm 43 for the purpose of setting the device in operation, arm 43 is provided with a push-button 50, the 55 stem 51 of which is riveted to the arm.

In operating the device, the winding key 11 is turned to the right, Fig. 1, winding the spring 7 until arm 13 on the winding spindle 10 engages stop pin 14, Fig. 6. 60 Then, upon depressing the push-button 50, the arm 43 is disengaged from the edge of slot 45 and springs to the position in which it is shown in Fig. 5, permitting rotation of the governor 15 and connected gearing under 65 the action of spring 7. Spindle 10 then ro-

tates in the direction indicated by the arrow in Fig. 6, while the stylus carrying arm 35 rocks around its pivot formed by post 36. This rocking motion of arm 35 is due to the stylus engaging the rotating record. Finally, the arm 13, Fig. 6, engages the arm 40, rocking the shaft 38 so that a rounded portion of the shaft engages the stylus carrying arm, lifting the same free from the record. The bent cam arm 37, also rigid with shaft 38, engages the extension 35.1 of arm 35, restoring this arm to normal position as shown in Fig. 5. Then arm 41, rigidly carried by shaft 38, engages the bent portion 42 of the spring arm 43, causing 70 the pad 21 to firmly grip disk 20 and prevent further rotation of the same and the mechanism geared thereto.

Although but one specific embodiment of this invention has been herein shown and described, it will be understood that numerous details of the construction shown may be altered or omitted without departing from the spirit of this invention as defined by the following claims.

I claim:—

1. A phonograph, comprising a diaphragm, a record support, means for driving said record support, a pivoted stylus carrying arm of spring material and adapted to resiliently bear toward said record support, a lever pivoted on the end of said arm, having a stylus mounted on one end thereof, and a connection between the opposite end of said lever and the center of said diaphragm.

2. A phonograph, comprising a diaphragm, a record support, means for driving said record support, a pivoted stylus carrying arm of spring material and adapted to resiliently bear toward said record support, a lever pivoted on the end of said arm, having a stylus mounted on one end thereof, a connection between the opposite end of said lever and the center of said diaphragm, and means operated by said driving means for disengaging the stylus from a record against the resilient action of the stylus carrying arm and returning the latter to its normal position.

3. A phonograph, comprising a diaphragm, a record support, means for driving said record support, a pivoted stylus carrying arm adapted to rock laterally of said record support, a lever pivoted on the end of said arm, having a stylus mounted on one end thereof, a connection between the opposite end of said lever and the center of said diaphragm, and means operated by said driving means for disengaging the stylus from the record and returning the stylus carrying arm to its normal position, said means comprising an oscillating shaft provided with a flattened portion below the path of travel of said stylus carrying arm

and a cam member rigid on said shaft in position to engage and cam said stylus carrying arm to its normal position.

4. A phonograph, comprising a record support, a driving mechanism therefor, a rotating governor for controlling the speed of said driving mechanism, a spring arm adapted to resiliently engage said governor,

and a cam member operated by said driving mechanism and shaped to force said spring 10 arm into engagement with said governor for the purpose of stopping the action of said driving mechanism.

Signed at Chicago this 25th day of Aug., 1916.

LEWIS COLE.
